UNITED STATES PATENT OFFICE.

ROBERT H. DOWLING, OF NEWARK, OHIO, ASSIGNOR OF TWO-THIRDS TO
CHARLES FOLLETT AND CHARLES H. FOLLETT, OF SAME PLACE.

CAR-COUPING.

SPECIFICATION forming part of Letters Patent No. 415,623, dated November 19, 1889.

Application filed September 16, 1889. Serial No. 324,043. (No model.)

To all whom it may concern:

Be it known that I, ROBERT H. DOWLING, a citizen of the United States, and a resident of Newark, in the county of Licking and State of Ohio, have invented certain new and useful Improvements in Devices for Coupling Cars; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a side elevation. Fig. 2 is a bottom view. Fig. 3 is a horizontal section. Fig. 4 is a top plan view, and Figs. 5, 6, and 7 are detail views.

This invention relates to certain improvements in car-couplings; and it consists of the novel combination and construction of parts, as will fully appear from the following description and accompanying illustration.

In the embodiment of my invention I employ 25 a draw-head A, having a curved or concave front end or face, one side of which terminates with a beveled extension a. The other side of said end of the draw-head A is provided with disk-like extensions b or lugs, one at top 30 and one at bottom, and between these lugs or extensions is an opening c, forming a seat for the knuckle or hook, the surface or wall of said opening being concave, and having the portions or surfaces immediately adjoining the disk-like lugs or extensions b, however, 35 formed in the arcs of true circles to provide bearings c' c' for said knuckles or hook. The opening or seat c merges or terminates in the knuckle or hook receiving chamber c² of the draw-head A.

B is the knuckle or hook, the beak of which stands nearly parallel with its inner tapering or tongue-like portion B'. Said knuckle is formed with a cylindric portion or axis b', 45 which rests or bears upon the bearings or arcs c' of the draw-head A, said axis or cylindric portion being of less width than the hook or knuckle, thus leaving bearing-surfaces d d upon the latter, having curvatures concentric 50 with and engaging the front edges of the disk-like extensions or lugs b of the draw-head.

Through the cylindric or axial portion b' of the hook or knuckle B and the extensions or lugs b is inserted the axial pin C, upon which 55 the hook or knuckle is carried, said pin having a spline-and-slot connection e e' therewith, but serving to pivot the hook or knuckle in the draw-head.

The extreme inner edge of the tongue-like portion B' of the knuckle or hook B engages a buttress-notch f in one side of the chamber of the draw-head A, and transfers the resistance from the knuckle or hook to the draw-head. This end of the tongue-like portion B' 65 of the hook or knuckle B is also adapted to swing in alignment with the coupling-pin opening g in the draw-head, in order to engage an inclined shoulder h of the holding pin D. When the holding-pin D is in a lowered position in the draw-head A, the lower 70 edge of the inclined shoulder h rests upon the bottom of the hook or knuckle receiving chamber c², and should the knuckle or hook be in its uncoupled position or swung outward, the tongue-like portion B' of said hook, in event of contact therewith of the beak of the hook of an opposite draw-head, will be pressed inward, and, engaging said shoulder, will carry said pin upward as it is passing 75 inward until said tongue-like portion passes said shoulder. Immediately after this the pin will automatically fall and prevent the return movement of said tongue-like portion of the hook or knuckle, and thus effect the 80 automatic locking of the coupling-knuckle.

The inner or rear side of the tongue-like portion B' of the hook or knuckle B has about midway between its inner end and axis or cylindric portion a hooked projection or tooth 90 i, which engages a corresponding notch or recess i' in one side of the chamber c², to effect the interlocking of the knuckle or hook B with the draw-head, whereby the knuckle or hook will be prevented when in its closed position from being withdrawn, even though its pivoting-pin should become displaced from the draw-head chamber.

The knuckle or hook is readily operated, so as to permit the uncoupling of the cars from one side of the latter by means of the hand lever or rod H, which is loosely connected at one end to a shouldered plate-like bar j, passed through a transverse aperture

j' in the lower projecting end of the pivoting or axial pin C, to which it is held by its shoulder, and a small key passed transversely through said pin. The rod or lever H also 5 passes through a slot K in the lower end of the pin D, in which it has a limited play, and engages when the knuckle or hook is in its uncoupled position in order to hold it in that position. A hook I is provided upon the under side of the draw-head. The rod or lever H extends outward sufficiently to be conveniently grasped and operated.

Having described this invention, what I claim, and desire to secure by Letters Patent, 15 is—

1. In a car-coupling, the knuckle or hook having the extreme inner end of its tongue-like portion engaging a notch or recess in the wall of the draw-head chamber, said notch 20 being arranged in rear of said inner end of the tongue-like portion, substantially as set forth.

2. In a car-coupling, the knuckle or hook having upon its inner or rear side between 25 its inner end and axis a hooked projection or stud engaging or interlocking with a corresponding notch in one side or wall of the draw-head chamber, and the draw-head having a notch in rear of and engaged by the 30 extreme inner end of the tongue-like portion of the knuckle-hook, substantially as set forth.

3. In a car-coupling, the holding-pin having an inclined shoulder and riding in an opening in the draw-head, the lower edge of said shoulder normally resting upon the bottom of the draw-head chamber, in combination with the hand lever or rod having a loosely-connected bar or link connected to the axial 35 pin of the knuckle or hook, said rod or lever passing through the lower end of said holding-pin, substantially as set forth.

4. In a car-coupling, the knuckle or hook having beyond its cylindric or axial portion concave bearings or shoulders engaging the 45 front edges of disk-like portions on the draw-head, substantially as set forth.

5. In a car-coupling, the knuckle or hook having the inner tongue-like portion adapted to move in alignment with the coupling-hook 50 opening of the draw-head and to engage the inclined shoulder on the holding-pin, in combination with the hand lever or rod passing through the lower end of said holding-pin and having a link-connection with the lower end 55 of the axial pin of the knuckle or hook, substantially as set forth.

6. In a car-coupling, the hand lever or rod having a loosely-connected bar connected to the lower end of the hook or knuckle pivot or 60 axial pin, said rod passing through the lower end of the holding-pin and engaging a hook upon the under side of the draw-head, substantially as specified.

7. The combination of the draw-head, the 65 knuckle or hook having a tongue-like portion adapted to move in alignment with the holding-pin opening in the draw-head, the pivoting or axial pin connecting the knuckle or hook to the draw-head, the holding-pin having an inclined shoulder having its lower 70 edge normally resting upon the bottom of the draw-head chamber, and the lever or rod having a loose bar connection with the loose end of the hook-pivoting pin and passing 75 through the lower end of the holding-pin and engaging a hook on the under side of the draw-head, substantially as specified.

In testimony whereof I affix my signature in presence of two witnesses.

ROBERT H. DOWLING.
